Attorney

UNITED STATES PATENT OFFICE.

JOHN K. CHAMP, OF PARIS, KENTUCKY.

TOOL.

1,101,165.

Specification of Letters Patent. Patented June 23, 1914.

Application filed October 13, 1913. Serial No. 794,969.

To all whom it may concern:

Be it known that I, JOHN K. CHAMP, a citizen of the United States, residing at Paris, in the county of Bourbon and State of Kentucky, have invented certain new and useful Improvements in Tools, of which the following is a specification, reference being had to the accompanying drawings.

This invention relates to new and useful improvements in tools and more particularly to the type known as pliers, the object of the invention being to provide a tool of the above character which is especially adapted for use as a wire working tool for twisting and splicing wire.

Another object of the invention is the provision of a tool of the above character which will possess advantages in points of efficiency and durability, is inexpensive of manufacture and at the same time is simple in construction and operation.

With the above and other objects in view, this invention consists in the novel features of construction and the combination and arrangement of parts to be hereinafter more fully described, pointed out in the claims and shown in the accompanying drawings, in which—

Figure 1 is a side elevation; Fig. 2 is a longitudinal sectional view; Fig. 3 is an edge view of the central portion of the pliers; Fig. 4 is a plan view illustrating the modified form of the invention; Fig. 5 is an elevation illustrating the manner in which the wire is spliced; Fig. 6 is an end elevation of the modified form; Fig. 7 is an elevation of a piece of wire illustrating the manner in which the wire is twisted by the use of my improved pliers. Fig. 8 is a detail perspective view of the movable block arranged between the jaws.

Referring more particularly to the drawings, 1 and 2 indicate the two outside handle portions of my improved pliers, which are formed adjacent their outer ends with the circular bearing members 3, said bearing members being pivotally connected by means of the transverse pin 4. The handles 2 are formed at their outer ends with the jaws 5 and 6 which are adapted to be arranged in opposed relation and are suitably provided at their outer ends with the spaced clamping portions 7, said clamping portions being provided upon their inner faces with a knurled surface 8 so that wire or other material may be readily gripped between the

clamping portions and held against movement. The jaws 5 and 6 are provided upon their inner faces and adjacent the clamping portions 7 with inwardly extending recesses 8', a portion of the walls thereof being provided with teeth, as shown at 9, said teeth being preferably arranged at the outer ends of the recesses.

The recesses 8' are adapted to form a substantially triangular shaped cavity, when the jaws 5 and 6 are in their closed position, adapted for the reception of a pyramidal shaped block 10 which is formed integral with the plates 11 and arranged between the outer ends thereof. The plates 11 are preferably elongated in form and are pivotally mounted at their intermediate portions upon the ends of the pivot pin 4. The inner ends of the plates 11 project beyond the circular portions 3 and are disposed between the handle members 1 and 2, a second handle member being arranged between the inner ends of the plates and secured thereto by means of the rivets 12. The second handle member which is arranged between the inner ends of the plates 11 is adapted to be operated to actuate the pyramidal-shaped block 10. Thus, when it is desired to place two separate wires within the recesses 8', upon opposite sides of the block, one of the wires is first placed in position and the handle member actuated to engage the block with the wire, so as to retain the same in the recess until the other wire has been placed within the second recess in the opposite side of the block. It will also be apparent that a loop formed by placing two ends of wire can be readily removed from the block and when pulling power is applied to either one of the wires, the loop formed will be closed by the strain upon the wire.

The jaws 5 and 6 are provided adjacent the circular portions with grooves 13 which space the circular portions 3 from the opposing jaws 5 and 6. It will be apparent that in splicing wire, the ends thereof are inserted between the clamping portions 7, each end being disposed upon opposite sides of the triangular block 10, one end extending out through one of the recesses 8' upon one side of the tool, and the other end extending out through the recess upon the opposite side. Thus upon turning movement of the pliers, the ends of the wires will be each twisted around the opposite wire, leaving a space between the wires, as illustrated by the

numeral 14 in Fig. 5. It will be apparent that the ends of the wires may be ordinarily twisted together by simply engaging the ends of the wires in a cross position between 5 the clamping portions 7 and rotating the pliers.

In Figs. 4 and 6, I have illustrated a slightly modified form of the invention wherein the clamping members 7' are provided at their ends with the grooved portions 8^a adapted to receive the ends of the wires when they are inserted between the clamping portions in a crossed position, as illustrated in Fig. 4. In this form of the 10 invention, it will be apparent that the same is to be used in merely twisting the wire, as illustrated in Fig. 7. It will be apparent that the ends of the wires may be readily twisted in the manner shown in Fig. 7 by 15 inserting the ends within the grooves 8^a in a crossed position, as shown in Fig. 4, and imparting turning movement to the pliers.

From the above description taken in connection with the accompanying drawings, it 20 will be readily apparent that I have provided a simple and durable tool whereby various forms and sizes of wire may be quickly and readily twisted, or the ends thereof quickly spliced together. It will 25 also be apparent that the clamping portions 7 of my improved pliers may be readily used for various other purposes to which 30 they may be applicable.

While I have shown and described the preferred form of my invention, it will be obvious that various changes in the details of construction and in the proportions may be resorted to for successfully carrying my 35 invention into practice without sacrificing

any of the novel features or departing from 40 the scope of the appended claims.

What I claim is:—

1. A device of the class described including handle members, circular members formed on said handles adjacent their outer 45 ends, a pivot pin extending through the center of said circular members to pivotally connect the handles, jaw members formed integral with the circular portions and arranged in opposed relation, said jaws being 50 formed upon their inner faces with recesses which are adapted to form a substantially triangular-shaped cavity when the jaws are in their closed position, plates arranged upon opposite sides of the circular portions 55 and mounted for pivotal movement upon said pin, a triangular-shaped block formed between the outer ends of said plates and arranged within said cavity, and a handle member arranged between and connected to 60 the inner ends of said plates.

2. A device of the class described including handle members having opposed jaw portions formed upon the outer ends and provided with recesses, a triangularly-shaped block arranged within the recesses of 65 the jaws, spaced plates formed integral therewith and arranged upon opposite sides of the jaws, and a handle member arranged between and connected to the inner ends of 70 said plates, as and for the purpose set forth.

In testimony whereof I hereunto affix my signature in the presence of two witnesses.

JOHN K. CHAMP.
